UNITED STATES PATENT OFFICE.

EDWARD M. GRIFFIN, OF PORTLAND, OREGON.

ORTHODONTIST'S LOCKING DEVICE.

Application filed September 20, 1922. Serial No. 539,446.

To all whom it may concern:

Be it known that I, EDWARD M. GRIFFIN, orthodontist, a citizen of the United States, residing at Portland, in the county of Multnomah and the State of Oregon, and having his address at 615 Stevens Building, in said city and State, have invented a new and useful Improvement in an Orthodontist's Locking Device, of which the following is a specification.

My invention relates to improvements in orthodontists locking devices wherein I have eliminated many of the faults in existing devices and have added to the art in the following particulars.

My improvement eliminates the elevation in the block and permits the arch wire to finish flush with the line of the arch wire on the tooth side of the wire, also a block and locking receptacle for the block are so made as to eliminate sharp corners, the same consisting of curves at all angle turns. A new and improved spiking arrangement is provided, the spike being made tapered in form, and when the same is in placement the small, or tapered point, is bent at right angles to the main staff, or shank, of the spike to hold the same in placement, the spike being made tapering in form, when in position, the end opposite, that of the one to be bent at right angles may be made to finish flush with the surface of the receptacle holding same thereby eliminating any projection that would be objectionable to the wearer of the same. When a change in pressure is required upon the arch wire the bent portion of the spike is removed on the smaller end by the action, of the grinding wheel, or by other means and the spike is pressed from position in the opposite direction from that which it was placed in position thus taking advantage of the taper which facilitates the removal of the spike. Another advantage of my improvement is accomplished in the method of securing the arch wire to the block by means of drilling the block and the arch wire and the soldering of the same in place by the use of a solder having a low fusing point, or one that melts at a low temperature, for by the use of the same a joint, or welding is accomplished without drawing the temper in the arch wire.

I attain these objects by the mechanisms illustrated in the accompanying drawings, in which—

Fig. 1 is a front view of the upper jaw

with the arch wire in place and clearly illustrating the lock in place, and Fig. 2 is a cross section view taken on line *a—a* of Fig. 1, in this view the arch wire and block are removed from the seat and a desired tension has been placed in the arch wire before the same is placed in position, in the seat, and the spike placed therein, the dotted position illustrates the position that the tooth will occupy, when the results are accomplished by the use of my lock. Fig. 3 is a plan view of the block before the same has been put in place upon the arch wire. Fig. 4 is an end view of the same. Fig. 5 is a plan view of the block in place upon the arch wire, and Fig. 6 is a cross section view of the same taken on line *b—b* of Fig. 5. Fig. 7 is a plan view of the seat partially broken away to more clearly show the construction of the same, and Fig. 8 is an end view of the same, also partially broken away. Fig. 9 is a plan view of the arch wire, block, seat, and spike assembled, and Fig. 10 is an end view of the same partially broken away to show the assembly of the same. Fig. 11 is a plan view of the seat attached to the band around the tooth, and Fig. 12 is a front view of the assembled seat, block, arch wire, and spike, this view is one of a terminal or end attachment in place attached to the band that is to pass and encircle the tooth to which it is to be attached. Fig. 13 is an end view of the assembled seat, block and spike, showing the spike in place before the same has been bent to placement on the lower side of the seat. Fig. 14 is an end view of the block that is to be attached to the arch wire at a location other than at a terminal or end of the wire and is shown slotted at the back for admission onto the arch wire. Fig. 15 is a plan view of the block in place on the arch wire as attached at the end terminal of the same.

Similar letters refer to similar parts throughout the several views:

1 is the arch wire to which the block 2 is made fast, this being accomplished by the drilling of a hole or other means as shown at 2^a in Fig. 4 if the block is to be used as an end terminal, but if the block is to be used other than an end terminal it is slotted as shown at 2^b in Fig. 14; after the block has been put in place upon the arch wire a hole 2^c is made in the block and the arch wire 110 and the same is then soldered in place by the use of a solder of a very low melting point,

thereby accomplishing the welding without drawing the temper of the arch wire, the object of soldering the arch wire to the block both at the hole or opening 2^c and 2^d is made possible the removal of all surplus metal at the base of the block and to eliminate elevation and to make possible a straight line of the arch wire and the base of the block, this is very essential in the practice of orthodontia for it has to do with the comfort of the correction devices that are placed in the mouth of the patient, for it reduces to a minimum the projection of the arch wire from the teeth and at the same time is far enough removed from the teeth to prevent its touching them, for when this is done the enamel coating of the teeth is subjected to a decaying action that is detrimental to them. 3 is the seat, which is attached to the band 4 that surrounds the tooth and holds the same in place. The elimination of the elevation at the back of the block, makes possible the location of the spike hole 4^a to be placed in the approximate center of the radius of the seat, the location of this hole was formerly near the outer edge of the same and can only be placed as shown in Fig. 7 and Fig. 11 by the elimination of the elevation as heretofore described. The location of the hole 4^a has a further advantage of making possible the rounding of all edges or corners of the seat thereby further adding to the comfort of the appliances when in place. 5 is the tapered spike which may be made pointed at both ends and bent to placement by the use of a pair of pliers or other similar tool, or it may terminate on its upper end by a head as shown at 5^a, or it may be terminated as shown in the dotted lines as shown at 5^b in Fig. 13.

Having thus described my invention, I wish to make the following claims therefor:—

1. An orthodontic appliance comprising a tooth engaging anchoring band, a seat rigidly secured thereto, an arch wire, a block rigidly secured to the arch wire, and detachable connections between the seat and block, the lower face of the arch wire being flush with the lower face of the block, said block having an elongated groove opening at the lower face thereof for receiving the arch wire, the arch wire receiving groove being spaced between the anchoring band and the detachable connections for the seat and block.

2. An orthodontic appliance comprising a tooth engaging anchoring band, a seat rigidly secured thereto, an arch wire, a block rigidly secured to the arch wire, and detachable connections between the seat and block, the lower face of the arch wire being flush

with the lower face of the block, said block having an elongated groove opening at the lower face thereof for receiving the arch wire, the arch wire receiving groove being spaced between the anchoring band and the detachable connections for the seat and block, said seat having a cross groove therein of a configuration similar to the external dimensions of the block with the block positioned in the seat groove. 65

3. An orthodontic appliance comprising a tooth engaging anchoring band, a seat rigidly secured thereto, an arch wire, a block rigidly secured to the arch wire, and detachable connections between the seat and block, the lower face of the arch wire being flush with the lower face of the block, said block having an elongated groove opening at the lower face thereof for receiving the arch wire, the arch wire receiving groove being spaced inwardly of the detachable connections for the seat and block, said seat having a cross groove therein of a configuration similar to the external dimensions of the block with the block positioned in the seat groove. 70

4. An orthodontic appliance comprising a tooth engaging anchoring band, a seat rigidly secured thereto, an arch wire, a block rigidly secured to the arch wire, and detachable connections between the seat and block, the lower face of the arch wire being flush with the lower face of the block, said block having an elongated groove opening at the lower face thereof for receiving the arch wire, said arch wire having a transverse opening therein communicating with the block groove for the reception of a solder possessing a relatively low fusing point, and being positioned at the transverse median line of the seat. 90

5. An orthodontic appliance comprising a tooth engaging anchoring band, a seat rigidly secured thereto, an arch wire, a block rigidly secured to the arch wire, detachable connections between the seat and block, the lower face of the arch wire being flush with the lower face of the block, said block having an elongated groove opening at the lower face thereof for receiving the arch wire, the arch wire receiving groove being spaced between the anchoring band and the detachable connections for the seat and block, said seat having a cross groove therein of a configuration similar to the external dimensions of the block with the block positioned in the seat groove, the cross groove in the seat being open at its outer side and said block lying flush with the outer walls of the seat groove. 105

EDWARD M. GRIFFIN.
